UNITED STATES PATENT OFFICE.

HARRY NEVILLE, OF LOS ANGELES, CALIFORNIA, ASSIGNOR OF ONE-FIFTH TO PATRICK SHEEDY, ONE-FIFTH TO GEORGE H. GOODWIN, ONE-FIFTH TO DANIEL KELLOGG, AND ONE-FIFTH TO WILLIAM F. MERRY, ALL OF LOS ANGELES, CALIFORNIA.

LOW-WATER ALARM.

1,164,664.

Specification of Letters Patent.

Patented Dec. 21, 1915.

Application filed July 11, 1913. Serial No. 778,498.

To all whom it may concern:

Be it known that I, HARRY NEVILLE, a citizen of the United States, residing at Los Angeles, in the county of Los Angeles and 5 State of California, have invented certain new and useful Improvements in Low-Water Alarms, of which the following is a specification.

This invention relates to improvements in 10 low water alarms for locomotive boilers by the use of which the explosion of such boilers is aimed to be prevented.

The immediate object of the invention is 15 to improve the construction of the apparatus shown and described in Letters Patent of the United States, Nos. 1,004,896 and 1,015,703 issued to me, whereby such apparatus is rendered more efficient and reliable, and the invention consists in the construction 20 and adaptation of the parts, as will be more fully hereinafter pointed out.

In the drawings, Figure 1 is a central vertical section of a device embodying the invention; Fig. 2 is a vertical section of a portion 25 of the same on a plane at right angles to the section plane of Fig. 1; Fig. 3 is a front view of a locomotive boiler equipped with the device; Fig. 4 is a side view of such a boiler similarly equipped, and Fig. 5 is a 30 detail of the boiler connection.

Referring to the drawings, 1 is the steam boiler of a locomotive on which, at a convenient place as hereinafter described, is arranged a cylinder 3 by means indicated at 35 4. At one side of the cylinder is a wing 5 in which is a passage 6 connected at the top and bottom to cross passages 7 and 8, the latter leading to a fitting 10 whereby a connection is made with the water space of the 40 boiler.

11 is an air space within the wing 5. Suspended in the cylinder 3 by a threaded joint is a cup 16 adapted to contain a mass of mercury 160. There is an annular space 9 45 surrounding the cup 16, which space is connected at the bottom by a space 90 connected in turn to the passage 8 by a vertical passage 91 the lower end of which is closed by a screw plug 12. The upper end 15 of the cup 50 16 is enlarged and expanded into an annular flange 17. The cup 16 is internally threaded and expanded to form a shoulder 19 above which it is internally threaded at 20 to receive a casing 21.

In the upper end of the casing 21 there is 55 secured a second casing 260 provided with a valve seat 22, and within this casing there is arranged a reciprocating valve 23 having a depending stem 33. Above the valve there is provided a passageway 24 leading to the 60 steam space of the boiler by a suitable pipe indicated at 261. Within the casing 21 is also a cylinder 200 in which there is slidably fitted a floating piston 201 provided at its lower end with a threaded extension 202 by 65 which its effective length may be varied.

The casing 21 is provided with an annular flange 250 having a steam passage 25. To this flange there is connected a conduit 280 leading to a control valve to the discharge 70 end of which there is connected a steam conducting pipe 29 leading to an alarm whistle arranged at any suitable point, and which pipe 29 is provided with a branch 301 which leads to and is connected with a suitable valve 75 mechanism 32 for controlling the fuel supply valve of the burner if liquid fuel is used, or to a water spray 320 for spraying the fire with water from the boiler in case solid fuel is used. The whistle and fire control mechanisms 80 form no part of the present invention and are therefore not illustrated in the drawings.

The body of the control valve is provided between its inlet and discharge ends with a 85 partition 281 provided with a seat 282 adapted to be engaged by a valve 28 having a stem 284 leading through a cap 285 adapted to close the upper portion of the valve body and held in position by a retaining nut 90 286. The lower inner edge 287 of the cap 285 constitutes a seat adapted to coöperate with the upper part of the valve 28. The valve stem 284 terminates in an upper head 288 between which and the nut 286 there is 95 placed a spring 289 which holds the stem 284 with its connecting parts normally in an open position. Passing through the cap 285 is a small leak passage 290.

Arranged within the upper part of the 100 cup 15 and the lower part of the casing 21 is a tube 41 provided with an annular flange 42 which, when the tube 41 is screwed down into the cup 16, engages the shoulder 19. Slidably mounted in this tube is a plunger 105 43, the upper end of which moves through a stuffing box 44. When the plunger 43 is raised sufficiently by the expansion of the

mercury, as is hereinafter explained, its upper end will engage the threaded extension 202 of the floating piston 200 which in turn being raised, will contact with the 5 valve stem 33, whereby the valve 23 will be lifted from its seat and steam will be permitted to pass through the valve from the pipe 261 to the pipe 280 and valve 28 to the pipe 29 to sound the alarm and actuate the 10 fire-extinguishing mechanism.

The upper end of the plunger 43 is provided with a slot 45 through which there is adapted to pass a lever 451 pivoted at 452. The lever 451 provides means for manually 15 moving the plunger and returning it to its normal position after it has been raised by the expansion of the mercury. It also provides means for testing the operative condition of the alarm by manually lifting the 20 plunger 43 into contact with the threaded extension of the floating piston 201. The lower end of the plunger 43 projects somewhat downwardly into the mercury cup 16 and there is an air space left between the 25 top of the mass of the mercury and the upper edge of the cup whereby the mercury can expand somewhat without moving the plunger. It will be readily understood that the plunger itself has to move somewhat before it reaches the threaded extension 202 on the floating piston 200, and the latter has to be actuated before it will contact with the valve stem 33 to move the valve 23.

In the upper end of the cup 16 there is 35 formed a drain passage 52 which communicates with a space between the upper end of the cup and the casing 21, thus permitting any water which might accumulate in this space to be drawn off. The floating piston 40 201 is provided with annular grooves indicated at 203, and it will be noted that the lower end of the stem 33 is not in direct contact with this piston but that there is a slight clearance between them. Also, the 45 piston is provided with a neck 204 in which the extension or timing screw 202 is inserted. This neck fits into an annular aperture in the casing 21 below the cylinder 200, and around this aperture is an annular flange 50 205 the upper edge of which is slightly above an annular passageway 206 formed in the casing and which communicates with a drain pipe 207. This annular flange forms a barrier to prevent water from the 55 condensed steam which leaks downwardly between the piston 201 and cylinder 200 from getting down into the lower part of the casing 21.

It will be noted that the valve 23 is 60 normally kept upon its seat by means of the pressure of the steam within and through the pipe 261 and the passageway 24, and that it is only lifted therefrom to permit the passage of the steam through the valve 65 into the small control valve 28 when the ex-

pansion of the mercury has been sufficiently great to move the plunger against the floating piston and this in turn against the valve stem.

In Figs 5 and 6 there is illustrated a 70 method of securing the device to the boiler in such a manner as to insure its most efficient operation. There is suitably secured to the side of the boiler at a convenient location an annular flange 60 having an aperture provided with a spherical or other suitable curved surface 61 and provided with an outwardly extending internally threaded annular flange 62. A hollow nut 63 externally threaded and provided internally with a 75 curved surface 64 corresponding in curvature to the surface 61 is adapted to be brought into threaded engagement with the threads of the annular flange 60. The annular flange and nut are adapted to inclose within their rounded surfaces a spherical member 65 into which there is adapted to be threaded a pipe 66 leading into the steam space of the boiler and a fitting 67 leading into the lower portion of the cylinder 3. The pipe 66 is so arranged that its inner 80 end is pivotally secured to a bracket 68 and its innermost end terminates at what is known as the neutral low water point of the boiler, *i. e.*, that point where the level remains constant for all variations longitudinal or lateral of the position of the boiler itself. This arrangement is for the purpose 85 of preventing the unnecessary actuation of the device and the sounding of the alarm 90 or the extinction of the fire until a real low water level is reached and to avoid the operation of the device, due to rocking or other vibrations of the locomotive.

The operation of the device is as follows: 105 The cup 16 is filled with mercury and the device is connected up to the boiler, a conduit leading from the passage 8 in the cylinder 3 to the neutral low water point of the boiler, as above described. As long as the connection to the boiler is under water the water 110 from the boiler will pass through the passage 8 into the cylinder 3 filling the latter and also the passages 6 and 7. The water thus let into the cylinder will be cooled by the 115 exposed position of the latter to the atmosphere and its heat will be insufficient to cause the mercury in the cup 16 to expand. When, however, the water in the boiler sinks below the level of the water in the passage 8 it 120 is, of course, below the level of the neutral low water point or very near it, the cylinder 3 will be drained of water and steam from the boiler will enter it and surrounding the cup 16 will heat the mass of mercury 125 therein and cause it to expand and, as it is confined in every other direction, it will rise into engagement with the plunger above it thereby forcing the plunger upward and, after a time depending upon the position of the 130

the extension of the floating piston, will contact with such extension and move the floating piston upward and this in turn will act upon the valve stem 33 and lift the valve 23 off of its seat and it will admit steam from the boiler through the valve opening and into the control valve 28, and as this valve is normally opened the steam will pass through the outlet 29 to the whistle which will sound the warning, and if the branch 30 is provided with the valves the steam will pass to the combustion-controlling device to shut off the fuel supply when liquid fuel is used, or to spray the fire with water from the boiler when coal is used. After the whistle alarm has been sounded the operator, of course, puts the water-filling apparatus of the boiler into action to fill the boiler with water up to its normal level. When this is done and the water again fills the cylinder 3 surrounding the mercury it will tend to cool the mercury. This, of course, will take some time before the mercury is cooled sufficiently to allow the plunger to drop, and, in the meantime, the steam from the boiler will be passing through both the valve 23 and the valve 28, and the whistle will continue to sound, but as soon as the contraction of the mercury has reached such a point that there is an appreciable distance between the upper end of the plunger and the lower end of the extension of the floating piston, the pressure of the steam upon the latter will cause it to descend and will automatically close the valve 23 above its seat, thus shutting off the steam, after which, of course, the valve 23 will be held upon its seat by the steam pressure. In the meantime, if it is desirable to shut off the whistle before this series of operations has automatically taken place, the plunger 43 and valve 23 can be returned to their normal positions by pulling down the lever 451, and the operator can also press down the stem of the control valve 28 by pressing down upon the cap 288. This will stop the further passage of the steam to the whistle and to the fire-extinguishing device, the valve 28 being held to its seat by the steam acting on its upper side. At the same time a slight flow of steam will take place and leak through the small passage 290 indicating to the operator that the valve 28 has been closed and that the apparatus is not in an operating condition. As soon as the valve 23 is returned to its seat, either automatically or through the actuation of the handle 451, the valve 28 will open automatically under the influence of its spring and then the apparatus will again be in an operative condition, but the water level cannot drop below the predetermined point.

The advantage of this construction, that is, by the use of a floating piston as compared with the coöperation of a plunger

directly upon the valve stem, and the valve stem acting against the action of a spring, is that in the construction described the steam itself serves by its elasticity the purpose of the spring formerly employed and holds the steam valve normally on its seat and, at the same time, it assists in the automatic return of the floating piston to its normal position and to the closing of the valve. That is, the device has fewer parts to accomplish the desired purpose than previous constructions. The advantage of the ball joint between the alarm device and the conduit leading to the neutral low water point is that the same construction of apparatus may be used with boilers having shells of different curvatures and permits of a ready adjustment of the parts, not otherwise possible. The cylinder 200 is both removable and changeable and consequently cylinders of different internal diameters and different lengths may be employed to suit different conditions.

What I claim is:

1. The combination with a controlling valve, of a thermostatic actuating device, a piston interposed between the thermostatic device and engaging the valve for transmitting movement from the thermostatic device to the valve to open said valve, and a passageway controlled by the valve for conveying steam to the piston to return the same after its movement by the thermostatic device.

2. In a device of the character described, a casing adapted to contain a steam valve, a stem for the valve, means for moving the valve stem including a cylindrical bearing and a floating piston adapted to reciprocate within the bearing and provided with a depending neck, a drainage passage within the casing and a barrier separating it from the piston neck.

3. In a device of the character described, a casing adapted to contain a steam valve, a stem for the valve, means for moving the valve stem including a cylindrical bearing and a floating piston adapted to reciprocate within the bearing and provided with a depending neck, a drainage passage within the casing and a barrier separating it from the piston neck and comprising an annular flange interposed between the passage and the barrier.

4. In an apparatus of the character described, a thermostatic element, a plurality of devices adapted to be successively moved one into engagement with the other after intervals of time by its expansion, a steam valve normally closed by the pressure of the steam, means for moving the valve by the last of the said series of devices, and mechanism operated by the steam pressure and controlled by such valve.

5. In an apparatus of the kind described,

a valve controlling a steam conduit leading from a boiler to an alarm element, a thermostatic element adapted to be exposed to the steam in the boiler when the water falls 5 below a certain point, and to be expanded by such exposure, a series of elements adapted to be successively moved after suitable time intervals, the first of the series moved from such expansion and the last of

the series moved against the valve, and 10 means for controlling the length of such time intervals.

In testimony whereof I affix my signature in presence of two witnesses.

HARRY NEVILLE.
